Application August 2, 1945, Serial No. 608,580

8 Claims. (Cl. 200—89)

1

This invention relates to electric circuit interrupting devices, and especially to automatic reclosing circuit breakers.

One object of this invention is to provide in an automatic reclosing circuit breaker, novel means for causing closely successive circuit interrupting operations of the breaker to have different time characteristics, and for preventing reclosure of the breaker in response to a predetermined number of closely successive circuit interrupting operations.

Another object of this invention is to provide in an automatic reclosing circuit breaker, fluid dashpot means adapted to determine the circuit opening time of the breaker and being controlled in a novel manner to cause closely successive circuit opening operations of the breaker to have different opening times, and which dashpot means actuates integrating means for preventing reclosure of the breaker in response to a predetermined number of closely successive circuit opening operations thereof.

Another object of this invention is to provide in an automatic reclosing circuit breaker, a single fluid dashpot means for controlling at least a circuit opening operation of the breaker and being provided with means varying the freedom of flow of fluid displaced by the dashpot means on closely successive operations of the breaker, together with means operated by said displaced fluid for preventing reclosing of the breaker in response to a predetermined number of closely successive breaker operations.

These and other objects of this invention will become more apparent upon consideration of the following description of preferred embodiments thereof when taken in connection with the attached drawing, in which:

Figure 1 is a longitudinal section view of a circuit breaker constructed in accordance with this invention, with most of the parts thereof within the breaker casing being shown in elevation.

Fig. 2 is an enlarged longitudinal section of a part of the circuit breaker mechanism shown in Fig. 1 but taken at an angle to the section of Fig. 1, and

Fig. 3 is a longitudinal section view of a modified form of a part of the breaker mechanism shown in Figs. 1 and 2.

The circuit breaker shown on the drawing is illustrated as being enclosed in a tubular casing 2 of insulating material, such as porcelain or the like, which is adapted to be supported intermediate its ends as by a supporting bracket 4, having packing material 6 interposed between the

2

bracket and casing. The lower end of casing 2 is provided with a closure disk 8 secured in position as by cementing or the like, and has a central aperture for receiving a terminal bolt 10. An enlarged head 12 is provided on terminal bolt 10 to be seated on the upper side of closure disk 8, with interposed packing material 14, and the terminal bolt is provided with a nut 16 for securing the bolt in position, and for also securing a terminal fixture 18 thereto.

15 A channelled supporting ring 21 is adapted to be secured about the upper end of casing 2 as by cast metal 20 or the like, which enters the channel portion of the ring and interlocks with peripheral grooves provided about the upper end of casing 2. A cover casting 22 is adapted to be secured over the upper end of casing 2 by means of bolts or the like (not shown) for securing the casting to supporting ring 21. Cover casting 22 is provided with a hollow chamber portion 24 which opens into casing 2, and it is also provided with an integral hood 26, for a purpose to be described.

20 A shaft 28 extends transversely of cover chamber 24 and has its ends mounted in opposite sides of the chamber for supporting a generally U-shaped spring support 30 which has the legs thereof apertured for rotatably receiving shaft 28. Spring support 30 is normally biased in a

25 counterclockwise direction by a coil compression spring 38, which is mounted on a rod 32 pivotally mounted at one end at 36 on one leg of support 30, and slidably mounted at its other end in an apertured lug 34 integral with cover casting 22. Spring 38 reacts between lug 34 and a

30 washer 40 secured to or integral with rod 32. Spring support 30 is normally prevented from rotating in a counterclockwise direction under the influence of spring 38 by a pair of toggle levers 42 and 44, with lever 42 pivotally connected

35 with one leg of support 30 at one end, and at its other end being pivoted to lever 44, which is in turn pivotally mounted as at 46 in the cover casting. Toggle lever 44 is provided with an integral handle extension 48 beneath hood 26, and

40 a hook eye 50 is located at the outer end of the handle extension for the reception of a hook stick or other operating member. Toggle levers 42 and 44 are normally held at their over-center position shown in Fig. 1 by spring 38, due to engagement of handle extension 48 with an adjustable stop bolt 52 provided beneath hood 26.

45 A coil reclosing spring 54 is also mounted on shaft 28 within chamber 24, and reacts at one end against the bight portion of support 30, and at its other end against the inner end of an oper-

ating lever 56 which is also pivotally mounted on shaft 28. A pair of links 58 of insulating material, such as fiber or the like, pivotally connect operating lever 56 to the upper end of a contact rod 60 which extends downwardly through casing 2 and into an interrupting chamber 62 provided in the lower portion of casing 2. Interrupting chamber 62 is formed of a tube 64 of insulating material, such as fiber or the like, having a bottom cap 66 secured thereon in any desired manner, with a fixed contact 68 mounted on the bottom cap so as to be positioned within interrupting chamber 62. Fixed contact 68 is adapted to cooperate with a contact head 69 provided on the lower end of contact rod 60 to open and close the circuit through the breaker upon appropriate movement of contact rod 60. Bottom cap 66 of the interrupting chamber is adapted to be electrically connected with terminal fixture 18 by means of a coil compression spring 70, reacting between the cap and head 12 of terminal bolt 10. Spring 70 is of a good electrical conducting resilient material, such as a copper alloy.

An upper end cap 12 is provided for tube 64 of the interrupting chamber being secured thereto in any desired manner, and is centrally apertured to slidably receive contact rod 60 and a sleeve 74 of insulating material provided on the rod to insulate it from cap 12. Sleeve 74 may be of any desired insulating material, such as fiber or a molded insulating material. Interrupting chamber 62 is adapted to be maintained in the position shown in Fig. 1 by a pair of spaced supporting plates 76 which may be integral with upper cap 72 of the interrupting chamber at one end, and at the other end they are integrally joined by a transverse supporting plate 77. A generally U-shaped solenoid supporting frame 78 has the lower leg thereof secured to supporting plate 77, as by bolts 80, and the upper leg thereof is adapted to be secured to cover casting 22 as by supports 81.

An annular coil 82 is adapted to be supported by frame 78, with the coil preferably being provided with a coating 84 of insulating material. Coil 82 is held in position substantially in alignment with opposed openings formed in the legs of supporting frame 78 by a dashpot sleeve 86, which is held in position by a shoulder provided on supporting plate 77. Contact rod 60 has an actuating sleeve 88 provided thereon in the region of coil 82, and this sleeve is provided with a collar 90 threaded into the upper end thereof for engagement with a shoulder 92 on the contact rod, for a purpose to be described. A tubular solenoid core 94 is also slidably mounted on contact rod 60 between sleeves 86 and 88 to form therewith a dashpot structure. Vent openings 96 are provided through the side wall of core 94 adjacent its lower end, to permit the free escape of liquid trapped within core 94. A light coil compression spring 98 is provided on contact rod 60 within actuating sleeve 88, and it reacts between collar 90 of the actuating sleeve and the closed end of core 94, to normally maintain the core at its lowermost position shown on the drawing.

The circuit through the breaker thus far described extends from a terminal fixture 99 provided on cover casting 22, by way of a conductor 100 to one side of coil 82, and then by a flexible conductor 102 to a supporting plate 104 secured on contact rod 60 against the upper end of insulating sleeve 74. The circuit then continues

in the closed position of the breaker to fixed contact 68 and terminal fixture 18. It will thus be observed that solenoid coil 82 is connected in series in the circuit. Supporting plate 104 on the contact rod also serves the purpose of pivotally supporting one end of a latch plate 106 having an opening for receiving contact rod 60 to permit limited pivotal movement of plate 106, and having a smaller opening adjacent the pivot point for receiving a latch rod 110.

When current flows through the circuit greater than a value predetermined by the rating of coil 82, solenoid core 94 will be attracted upwardly by coil 82. Initial upward movement of core 94 will compress spring 98 but will not separate the contacts until the bottom of the core engages the lower end of actuating sleeve 88 and moves the sleeve upwardly until collar 90 engages shoulder 92 of the rod. As soon as contact head 69 separates from fixed contact 68, an arc will be drawn which will create pressure within interrupting chamber 62 to further separate the contacts. As soon as the arc is extinguished, the chamber may be automatically vented or the pressure therein otherwise dissipated so that reclosing spring 54 will be free to move contact rod 60 downwardly to cause engagement of contact head 69 with fixed contact 68. The structure and operation thereof described above is quite similar to that disclosed in J. M. Wallace Patent No. 2,333,604, issued November 2, 1943, on "Circuit Interrupter," and assigned to the same assignee of this invention. In the Wallace patent, separation of the contacts is delayed a predetermined time after the occurrence of an overload sufficient to cause coil 82 to attract core 94 upwardly by the dashpot action of the core working between sleeves 86 and 88. Moreover, in reclosing the circuit, downward movement of contact rod 60 is also adapted to be correlated with downward movement of core 94 and, consequently, be delayed by the dashpot action thereof. This correlation of the movement of contact rod 60 and core 94 in closing the circuit is accomplished by latch plate 106 which wedges on latch rod 110 upon attempted downward movement of the contact rod, due to the action of spring 108, to thus latch the contact rod in the uppermost position to which it is moved during a circuit opening operation, and this latch is released by engagement with the outer end of latch plate 106 of core 94 in its downward movement. Contact rod 60 will thus move downwardly toward closed circuit position at the same rate core 94 is moved downwardly by spring 98 and by the action of gravity, until the lower reduced portion of latch rod 110 is reached, whereupon latch plate 106 can no longer bind on the rod and final closing movement of the contacts will, therefore, occur relatively rapidly.

For the purpose of providing dashpot action of core 94 between sleeves 86 and 88, a sleeve 112 is provided closely fitting within the upper end of dashpot sleeve 86, and having an outwardly turned flange at its upper end held against the upper leg of solenoid supporting frame 78, by a coil compression spring 114 reacting between this flange and the upper end of sleeve 86. The lower end of sleeve 112 is provided with a relatively large fluid inlet opening 116 which is normally closed by a check valve disk 118 held against the opening by a coil compression spring 120. The upper leg of supporting frame 78 is provided with a fluid passage 122 leading from the upper end of sleeve 112 to an opening in which is threaded a cylindrical sleeve 124. The upper end of sleeve

124 has secured therein a plug disk 126 provided with a small opening 128 of a size to receive a rod 132 secured to a piston member 130 which is slidably mounted in sleeve 124. Rod 132 may extend below piston 130 as at 136, to form a stop for downward movement of the piston. The upper end of rod 132 may be tapered as at 134 so that it may readily enter aperture 128 in disk 126.

It will now be observed that in operation, with casing 2 filled with an arc-extinguishing liquid, preferably up to the level L, that when solenoid coil 82 becomes energized sufficiently to attract core 94 upwardly and effect a circuit opening operation, such upward movement of core 94 will displace liquid trapped above the core between sleeves 86 and 88 up through sleeve 112, by displacement of check valve disk 118, through passage 122, and will cause upward movement of piston 130 in a relatively unrestrained manner. Now when the circuit is reclosed, downward movement of core 94 will be restrained, because check valve disk 118 will close inlet 116, and liquid can enter the dashpot space between sleeves 86 and 88 only through the relatively small clearances between these sleeves and core 94. Upon reclosure of the circuit if the fault or other condition which caused the opening operation has cleared, piston 130 will gradually sink back to the position shown in Figs. 1 and 2. However, if the fault or condition still remains on the circuit upon the first reclosure of the breaker, core 94 will be immediately attracted upwardly again. Depending upon the length of sleeve 124, the upper end of rod 134 may this time be moved into opening 128 in the upper end of sleeve 124 to thereby restrict the flow of liquid from the upper end of sleeve 124, and thus slow down upward movement of core 94 inasmuch as it is necessary that fluid displaced by such upward movement of the core be forced through the relatively small clearance between rod 132 and opening 128, and thus delay opening of the contacts. If desired, sleeve 124 may be made longer so that rod 132 will not enter opening 128 until the third closely successive circuit opening operation, so that the first two closely successive circuit opening operations will occur relatively rapidly, and the third opening will be delayed. In any event, when the breaker automatically recloses the second time, resetting of piston 130 may occur as described above if the fault or condition causing opening of the breaker has disappeared. However, if it has not disappeared, the breaker will immediately reopen and upward movement of the core 94 will again be delayed as rod 132 will be in opening 128.

Inasmuch as rod 132 is advanced a predetermined amount each time the breaker operates to open the circuit, this is made use of by positioning sleeve 124 substantially directly beneath toggle lever 42, so that when rod 132 has been advanced an amount due to a predetermined number of closely successive circuit interrupting operations, it will be moved into engagement with toggle lever 42 and cause this lever together with the lever 44 to be moved upwardly overcenter, and thus release spring 38 to rotate spring support 30 in a clockwise direction to maintain the contacts in an open circuit position. Following such an automatic lockout of the breaker contacts, they can be reclosed only by manually returning handle 48 from its lockout position where it projects below hood 26 to the position shown in Fig. 1, to move the toggle levers back overcenter and permit spring 54 assisted by the force of gravity to reclose the contacts.

The breaker described above may be provided with various accessories such as a receptacle 138 integral with the cover structure within chamber 24 for mounting a lightning arrester unit therein to be electrically connected with coil supporting frame 78, as by a conductor 140. An operation counter 142 may be mounted beneath hood 26 if desired, and be actuated by a connecting rod 144 from a lever 146 which moves in accordance with movement of contact operating lever 56. Such a counter 142 should be positioned beneath hood 26 so that the number of operations registered thereon is readily visible. A filler plug 148 may also be provided for the cover casting to obtain communication with chamber 24 and permit replenishing the supply of arc extinguishing liquid within casing 2.

Instead of providing for the first, or the first two circuit opening operations in any series of closely successive circuit opening operations to occur relatively rapidly as in the embodiment of the invention illustrated in Figs. 1 and 2, with the circuit opening operations following these being delayed a predetermined time after the occurrence of the predetermined conditions or overload causing the opening operation, it may be desirable to provide some other sequence of relatively fast and slow opening operations, and this may be accomplished by varying the form of rod 132. Thus, in Fig. 3, there is illustrated a rod 150 provided with a portion 152 beneath piston 130 forming a stop, and provided intermediate its ends with a portion 154 reduced in cross-section area so that a relatively large upper end 156 of substantially the same size as opening 128 in disk 126 is provided normally closely adjacent the opening so that the tapered end 158 is partially in the opening.

In the operation of this embodiment of the invention, it will be observed that the first circuit opening operation in any series of closely successive circuit opening operations will be delayed because enlarged portion 156 of rod 150 will be positioned within opening 128 in the upper end of sleeve 124 so as to restrict flow of liquid displaced by upward movement of solenoid core 94. In the event the breaker opens immediately after a first reclosure, the reduced part 154 of rod 150 will be within opening 128 so that a relatively free flow of the fluid displaced by upward movement of core 94 will occur on the second circuit opening operation, so that this operation will occur relatively rapidly. It will be apparent that a third closely succeeding operation will occur relatively slowly as will subsequent operations until lockout occurs.

It is apparent that with this invention there is provided a simplified means for controlling the time characteristic of circuit opening and closing operations of automatic reclosing circuit breakers, which is adapted to provide a predetermined sequence of relatively fast and slow circuit opening operations in any sequence of a predetermined number of closely successive circuit opening and closing operations. Moreover, in the event a lesser number of circuit opening and closing operations occurs, the device will reset so that the breaker will operate through the same sequence of relatively fast and slow circuit openings in the event the predetermined conditions appear on the circuit at a later time. In addition to the above, the same device is also adapted to integrate closely successive circuit interrupting operations so as to operate lockout means to maintain the circuit breaker contacts

open after the occurrence of a predetermined number of such closely successive circuit interrupting operations. The very simple mechanism disclosed herein for obtaining these various results may be made to provide any desired sequence of relatively fast and slow circuit opening operations merely by varying the shape of rod 132, as illustrated, for example, in Figs. 2 and 3. It is obvious that the breaker can thus be made to open with time delay on the first operation and with instantaneous characteristics on subsequent operations, or to open substantially instantaneously on the first or first and second operations and with time delay on subsequent operations, or in other sequences of relatively fast and slow circuit opening operations.

Having described preferred embodiments of this invention in accordance with the patent statutes, it is desired that the invention be not limited to the particular structures disclosed, inasmuch as it will be apparent particularly to persons skilled in this art that many modifications and changes may be made in these particular structures without departing from the broad spirit and scope of this invention.

We claim as our invention:

1. An automatic reclosing circuit breaker comprising, separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, vent means for said dashpot means normally freely passing an amount of fluid equal to that displaced by said dashpot means during a circuit opening operation, a member which is advanced a predetermined amount from a normal position in response to each circuit opening and closing cycle of operation of the breaker for restricting the flow of fluid through said vent means in response to a predetermined operation in any series of closely successive operations to delay the following circuit opening operation of such a series of operations, said member being biased to return to its normal position and having means for delaying such return movement, and means responsive to advancement of said member an amount greater than that required to restrict said vent means for terminating such a series of operations.

2. An automatic reclosing circuit breaker comprising, separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, vent means for said dashpot means normally freely passing an amount of fluid equal to that displaced by said dashpot means during a circuit opening operation, a member which is advanced a predetermined amount in response to each circuit opening and closing cycle of operation of the breaker for restricting the flow of fluid through said vent means in response to a predetermined operation in any series of closely successive operations to delay the following circuit opening operation of such a series of operations, means responsive to advancement of said member an amount greater than that required to restrict said vent means

for terminating such a series of operations, said member being biased to return to a normal position, and fluid dashpot means delaying said return movement of said member.

5 3. An automatic reclosing circuit breaker comprising, separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, vent means for said dashpot means normally freely 10 passing an amount of fluid equal to that displaced by said dashpot means during a circuit opening operation, a member which is advanced a predetermined amount in response to each circuit opening operation of the breaker for restricting 15 the flow of fluid through said vent means in response to a predetermined circuit opening operation in any series of closely successive circuit opening operations to delay the following circuit opening operation of such a series of operations, 20 means responsive to advancement of said member an amount greater than that required to restrict said vent means for terminating such a series of operations, means for delaying return movement of said member and means for automatically 25 closing said vent during at least a portion of each circuit closing operation of the breaker to delay closing of said contacts.

4. An automatic reclosing circuit breaker comprising, separable contacts, means responsive to 30 a predetermined condition of the circuit for causing separation of said contacts to open the circuit, means responsive to a circuit opening operation for automatically closing said contacts, fluid dashpot means for delaying separation of said 35 contacts a predetermined time after the occurrence of said predetermined condition, vent means for said dashpot means normally freely passing an amount of fluid equal to that displaced by said dashpot means during a circuit opening operation, a member which is advanced a predetermined amount in response to each circuit opening operation of the breaker for restricting 40 the flow of fluid through said vent means in response to a predetermined circuit opening operation in any series of closely successive circuit opening operations to delay the following circuit opening operation of such a series of operations, means responsive to advancement of said member an amount greater than that required to restrict said vent means for terminating such a series of operations, means for automatically 45 closing said vent during at least a portion of each circuit closing operation of the breaker to delay closing of said contacts, said member being biased to return to a normal position, and fluid dashpot means delaying said return movement of said member.

5. An automatic reclosing circuit breaker comprising, separable contacts, means responsive to 50 a predetermined condition of the circuit for causing separation of said contacts to open the circuit, means responsive to a circuit opening operation for automatically closing said contacts, fluid dashpot means for delaying separation of said 55 contacts a predetermined time after the occurrence of said predetermined condition, a vented chamber for receiving fluid displaced by operation of said dashpot means, one-way valve means permitting flow of displaced fluid into said chamber but preventing outflow thereof, piston means 60

in said chamber, said piston means biased to a normal position in said chamber free of the chamber vent and from which it is advanced a predetermined amount by said displaced fluid at least on each circuit opening operation of the breaker, said piston means being advanced sufficiently to restrict said chamber vent on a predetermined circuit opening operation in any series of closely successive circuit opening operations, and means responsive to still further advancement of said piston means for terminating such a series of operations.

6. An automatic reclosing circuit breaker comprising separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, a vented chamber for receiving fluid displaced by operation of said dashpot means, piston means in said chamber, said piston means biased to a normal position in said chamber free of the chamber vent and from which it is advanced a predetermined amount by said displaced fluid at least on each circuit opening operation of the breaker, said piston means being advanced sufficiently to restrict said chamber vent on a predetermined circuit opening operation in any series of closely successive circuit opening operations, means responsive to still further advancement of said piston means for terminating such a series of operations, and check valve means permitting flow of said displaced fluid solely in a direction into said chamber.

7. An automatic reclosing circuit breaker comprising, separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, a vented chamber for receiving fluid displaced by operation of said dashpot means, one-way valve means permitting flow of displaced fluid into said chamber but preventing outflow thereof, pis-

ton 50

ton means in said chamber, said piston means biased to a normal position in said chamber from which it is advanced a predetermined amount by said displaced fluid at least on each circuit opening operation of the breaker, said piston means having a portion normally spaced from the chamber vent but adapted to enter said chamber vent when said piston means is advanced an amount determined by a predetermined circuit opening operation in any series of closely successive circuit opening operations to delay the next opening operation of such a series of operations, and means positioned to be engaged by said portion when advanced a predetermined further amount to prevent reclosure of said contacts.

8. An automatic reclosing circuit breaker comprising, separable contacts, means responsive to a predetermined condition of the circuit for causing separation of said contacts to open the circuit, means responsive to a circuit opening operation for automatically closing said contacts, fluid dashpot means for delaying separation of said contacts a predetermined time after the occurrence of said predetermined condition, vent means for said dashpot means normally freely passing an amount of fluid equal to that displaced by said dashpot means during a circuit opening operation, a member which is advanced a predetermined amount from a normal position in response to each circuit opening and closing cycle of operation of the breaker, said member being biased to return to its normal position and having means for delaying such return movement, vent opening and closing means operated by said member for altering the time characteristic of successive circuit opening operations, and means responsive to advancement of said member a greater amount for terminating such a series of operations.
